ASSEMBLING APPARATUS

George E. Berggren, Baltimore, Edward Bertalan, Glen Arm, and Alexander Logan, Dundalk, Md., assignors to Western Electric Company, Incorporated, New York, N. Y., a corporation of New York

Application November 30, 1944, Serial No. 565,840

6 Claims. (Cl. 29—200)

1

This invention relates to assembling apparatus and more particularly to apparatus for assembling annular insulating and spacing discs on a central conductor used in making coaxial cables.

This application is a continuation-in-part of copending application, Serial No. 470,746, filed December 31, 1942.

Coaxial cables usually comprise a solid central conductor and a tubular outer conductor, which is held away from and maintained coaxially of the central conductor by means of wafer-like spacing and insulating discs. Such cables have been made in the past by stringing insulating discs having central apertures therethrough upon the central conductor, much in the same manner that beads are strung upon a strand, and then forming the tubular outer conductor over the discs in any suitable manner. It also has been suggested that the discs be molded directly upon the central conductor, but this method requires complicated and expensive apparatus.

Another method of making these cables that has been used heretofore was to punch a number of insulating discs from a strip of suitable material, such as hard rubber, in a punch press having a punch and die of such configuration that the discs had central apertures for receiving the central conductor and radial slots extending from the central openings to the peripheries of the discs through which the central conductor was forced into the central openings. Usually the radial slots had constricted portions, and the discs were sufficiently resilient to permit the slots to open up as the central conductor passed through the constricted portions and to snap back around the conductor after the conductor had entered the central apertures in the discs. As a result, the discs engaged the central conductor firmly and could not be displaced readily.

Polystyrene has been suggested as a suitable material to use in making the insulating discs, but pure polystyrene is so brittle that slotted discs made therefrom cannot be applied to central conductors without breaking the discs. Hence, when polystyrene discs are used they must be threaded or molded upon central conductors. It is obvious that when long, continuous central conductors are employed, it is impractical to thread centrally perforated discs upon such conductors, while apparatus for continuously molding discs upon such central conductors is costly and complicated.

2

The application of slotted discs to central conductors may be performed with satisfactory results when the discs are made of a relatively hard, resilient material, such as hard rubber, but this method is unsatisfactory when discs made of soft plastics are employed.

One of the plastic materials, which has properties that render insulating discs made therefrom especially suitable for use in the manufacture of coaxial cables, is the one obtained by polymerizing ethylene. This material, which is called "polyethylene," is a moderately soft, pliable material, having a high molecular weight and possessing excellent insulating characteristics. 15 This material may be obtained from several sources, one of which is E. I. Du Pont de Nemours & Company, which sells it under the trade name "Polythene."

Polyethylene is sufficiently hard to permit insulating discs made therefrom to maintain their shapes under ordinary circumstances, but it is soft enough to cause some manufacturing difficulties to arise when slotted discs are punched from strips thereof. Furthermore, when slotted 20 discs of the type formerly made of hard rubber were made of polyethylene and were forced upon a central conductor, the sides of the slots occasionally were deformed by the passage of the conductor therethrough. As a result, the discs 25 would not adhere firmly to the central conductor, and would tend to slide along the conductor or might even come off the conductor. In addition, it is relatively easy to force such 30 discs off the conductor by a thrust applied on the sides of the discs opposite the slots and substantially longitudinally of the conductor, because the small amount of the material in the 35 walls of the slots against which the conductor presses under those circumstances does not possess enough sheer strength to hold the discs in 40 place.

An object of the invention is the provision of 45 simple and effective apparatus for assembling articles.

An apparatus embodying the invention operates as follows: a single hopper feeds annular insulating discs through two sets of separate feed paths to a pair of feed wheels, which carry 50 the discs past knives to cut a radial slit in each annular disc and which alternately slide the discs upon a constantly moving central conductor with a wiping motion, the slits in the discs being held slightly open and maintained in 55 the slots in the feed wheels by means of re-

tainers until the discs reach the central conductor, whereupon the discs pass off the retainers upon the central conductor and the slits therein are free to close up around the central conductor.

A complete understanding of the invention will be had by reference to the following detailed description, when considered in conjunction with the accompanying drawings, wherein

Fig. 1 is a front elevational view of an apparatus for applying annular insulating and spacing discs to a central conductor, which apparatus embodies the apparatus of the present invention and provides means by which the present invention may be practiced;

Fig. 2 is an enlarged, fragmentary, detailed sectional view taken substantially along the line 2—2 of Fig. 1 in the direction of the arrows;

Fig. 3 is an enlarged, fragmentary, sectional view taken substantially along the line 3—3 of Fig. 1 in the direction of the arrows;

Fig. 4 is a fragmentary, sectional view taken substantially along the line 4—4 of Fig. 3 in the direction of the arrows and showing details of one of the feed wheels and its co-operating parts;

Fig. 5 is a greatly enlarged detailed view in section taken substantially along the line 5—5 of Fig. 4 in the direction of the arrows and showing an insulating disc being carried by a feed wheel, together with the retainer provided for holding the discs on the feed wheel and for holding open the slits in the discs;

Fig. 6 is a fragmentary plan view, partly in section, of the hopper and its communicating disc-carrying mechanisms for directing the annular discs to the feed wheels;

Fig. 7 is an enlarged, fragmentary, vertical, sectional view taken substantially along the line 7—7 of Fig. 6 in the direction of the arrows;

Fig. 8 is a detailed, elevational view showing a knife for slitting the insulating discs;

Fig. 9 is an enlarged, fragmentary perspective view of the blade end of the knife shown in Fig. 7 and illustrating how the knife cuts slits in the annular discs;

Fig. 10 is a detailed view showing one of the annular discs before it is slit;

Fig. 11 is a cross-sectional view of a coaxial cable utilizing the unit comprising the central conductor and insulating discs assembled in accordance with the present invention, and

Fig. 12 is a view in perspective of a short length of coaxial cable, which utilizes the unit formed in accordance with the present invention, part of the tubular outer conductor being broken away to illustrate the positioning of the insulating and spacing discs between the tubular outer conductor and the central conductor.

Referring to the drawings, wherein like reference characters designate the same parts throughout the several views, a main support member 15 is provided for supporting a hopper designated generally by the numeral 16, feed wheels 17 and 18 and transfer devices designated generally by the numerals 19 and 20. The hopper 16 and the transfer device 19 are interconnected by a guide designated generally by the numeral 21 and the hopper 16 and transfer device 20 are interconnected by a guide designated generally by the numeral 22. The details of the hopper 16 are shown most clearly in Figs. 6 and 7 and, by reference to these figures, it will be seen that the hopper includes an inverted cone-shaped bin 23, into which annular discs may be dropped haphazardly. The bin 23 terminates at its lower

end in an annular member 24 surrounding a substantially cone-shaped agitator 25. The agitator 25 may be rotated within the annular member 24 in any suitable manner, for example, by a motor (not shown) driving a transmission or gear reducing unit 26, which also supplies power to drive a pair of shafts 27 and 28 on which the feed wheels 17 and 18 are mounted. This driving connection may be of any suitable construction and, since the details thereof are not pertinent to the present invention, they have not been described in great detail.

Extending upwardly from the unit 26 is a shaft 29, on which the cone 25 is supported for rotation within the bin 23. The cone 25 is provided with a flattened cylindrical lower end 30, which, together with the bin 23, defines an annular slot 31 into which annular discs 32—32, as shown in Fig. 7, may drop when the agitator 25 is rotated within the bin 23. Fixed to diametrically opposed surfaces of the agitator 25 are a pair of feed fingers 33 and 34 made of steel wire and bent to extend into the annular slot 31 formed by the annular member 24 and the flattened lower surface of the agitator 25, whereby any discs which drop into the slot move around in the slot as the agitator 25 rotates. The feed fingers 33 and 34 are sufficiently resilient so that if the guides 21 and 22 are filled with discs, the feed fingers will bend and pass over the tops of those discs in the slot 31.

At opposite sides of the annular member 24, there are provided means for directing discs 32—32 from the slot 31 into the guides 21 and 22 and these devices comprise support plates 40 and 41 fixed to the annular member 24 and carrying assemblies 42 and 43, respectively, for directing the discs into the guides 21 and 22. Both of the assemblies 42 and 43 are of exactly the same construction and, accordingly, only the assembly 42 will be described in detail. The assembly 42 comprises two plates 44 and 45 suitably fixed together in abutting relation. The plate 45 has a groove 46 formed therein which, when the assembly 42 is mounted in place, as shown in Figs. 6 and 7, comprises a tangential prolongation of the annular slot 31. The groove 46 cooperates with the flat surface of the plate 44 to form a passageway into which the discs 32—32 will be directed by an extending finger 45, which is formed integrally with the plate 45 and extends into an annular slot 48 formed on the flat lower surface of the cone-shaped agitator 25. The finger 47 serves to strip the discs out of the slot 31 and guide them into the groove 46. The annular member 25 is cut away, as shown at 49 and 50, to receive the plates 44 and 45 so that the plates 44 and 45 will cooperate to guide the discs into the guides 21 and 22.

The guides 21 and 22 are of the same general construction except that they are bent at different angles for guiding the discs 32—32 fed therein from opposite sides of the hopper 16. Each of the guides 21 and 22 comprises, as shown most clearly in Fig. 2, a strip 51 having a slot 52 cut therein, in which the discs 32—32 will drop. Attached to the strip 51 is a thin plate 53, which partially closes the slot 52 and will serve to retain the discs in position therein while they are guided down from the hopper to the transfer devices 19 and 20. A slit between the plate 52 and strip 51 permits visual inspection of the supply of discs 32—32 in the guides and, if desired, air blasts may be directed against the discs to insure that they move down the guides.

At the transfer devices 19 and 20, the guides 21 and 22 terminate in a transfer block 60, which has a slot 61 formed therein, which slot comprises a prolongation of the slot 52 in the strip 51. The slot 61 is in communication with a plunger slot 62, in which a plunger 63 is slidably mounted. The plunger 63 is mounted upon a connecting member 64, which is formed integrally with a cam projection 65. A spring 66 normally urges the camming projection 65 and connecting member 64 to the left, as seen in Fig. 2, to carry the camming projection 65 into engagement with a cam 67. The cam 67 is mounted upon the shaft 28 and is positioned in back of the main support member 15. The shaft 28 also carries a gear 63 in mesh with a gear 69 fixed to the shaft 27 and the shaft 27 also carries a cam member 79 of exactly the same construction as the cam 67. Thus, the construction is the same for both transfer devices 19 and 20.

A plate 71 fixed to the main support member 15 serves as a guide for the connecting member 64 and the main support member 15 is provided with a suitable aperture 22, which permits the connecting member 64 and camming projection 65 to reciprocate in a guide slot 73 formed in the plate 71. Each time the camming projection 65 strikes a low point on the cam 67, one of the discs 32-32 will be transferred from the slot 61 into the feed wheel 18, which is provided with a series of notches 74-74 for receiving the discs. It should be noted that the notches 74-74 alternate with notches 75-75 around the periphery of the feed wheel 18 and that the notches 75-75 have one surface cut away for a purpose to be described hereinafter.

As the feed wheel 18 rotates, an annular disc 32 will be fed into each of the notches 74-74 cut therein and will be carried around with the feed wheel 18. Just below the position where the feed wheel 18 receives the annular discs 32-32, there is provided a knife 76 (Figs. 4, 8 and 9), which will cut a radial slit 77 (Figs. 9, 11 and 12) in each disc as the discs are carried past the knife. Extending peripherally of the feed wheel 18 in direct vertical alignment with the knife 76 is a retainer 78, with which the slit 77 in each annular disc will engage and with which the edge of the central aperture 79 of each disc will engage (Figs. 4 and 5), whereby the discs 32-32 will be forced to travel around with the feed wheel 18. The retainer 78 extends to a position where it is engaged on its upper edge by a central conductor 80, on which the discs 32-32 are to be assembled. The retainer 78 has the same thickness as the bottom portion of the knife 76 and the discs which are slit by the knife pass directly from the knife onto the retainer. The retainer holds the slits formed in the discs slightly open until the discs reach the central conductor 80, which permits the central conductor to slide freely into and through the slits into the central apertures 79-79 in the discs.

The central conductor 80 is fed through a guide 81, which cooperates with other guides and feed mechanisms (not shown) for guiding the conductor past the feed wheels 17 and 18 in timed relation to the rotation of the feed wheels. The construction of the slitting mechanism at the transfer device 20 is exactly the same as at the transfer device 19. There is provided a knife similar to the knife 76 for slitting the discs radially and a retainer 82 similar to the retainer 78, but shorter than the retainer 78, for guiding those discs 32-32 which are fed to the feed wheel 17

to a position where the discs will be forced onto the central conductor 80 and for holding open the slits in the discs until they reach the central conductor. The feed wheel 17 is provided with notches 74-74 and 75-75 alternately about its periphery in the same manner as is the disc 16, since it is desired to apply the discs 32-32 from opposite sides of the central conductor 80. When a tubular outer conductor 83 is applied around the discs 32-32 co-axially with the central conductor 80, the discs 32-32 will hold the tubular outer conductor spaced an equal distance from the central conductor 80 throughout the length of the cable and will insulate the two coaxial conductors from each other.

As is evident from Figs. 8 and 9, each of the knives illustrated by the knife 76 comprises a flat shank 88 having a bead 84 formed at the end thereof adjacent to its companion feed wheel. The bead 84 has a raised point 85 at the top thereof designed to cause the bead to enter the central apertures 79-79 of the discs 32-32 so that a curved cutting edge 86, which is formed at the upper edge of the shank and extends from the point 85 to a point on the shank beyond the outer edges of the discs, may cut a radial slit 77 in each disc as the discs 32-32 are carried past the knives by the feed wheels.

Since the discs 32-32 are applied to the central conductor from opposite sides, the notches 74-74, which carry the discs 32-32 on both of the feed wheels 17 and 18, are arranged so that when one of the discs 32-32 is forced onto the central conductor 80 by the feed wheel 18, one of the notches 75-75 in the feed wheel 17 will receive the upper end of the disc. Likewise, when the feed wheel 17 carrying a disc 32 in one of its notches 74-74 reaches the position where the disc is to be forced onto the central conductor, the notch 74 in the feed wheel 17 which carries the disc will be in alignment with a notch 75 on the feed wheel 18 and the latter notch will receive the disc.

In the operation of the present machine a supply of annular insulating and spacing discs 32-32 may be thrown haphazardly in the hopper 16, from which they will be fed by the feed fingers 34 and 35 into the guides 21 and 22. As the discs 32-32 are fed into the guides, they will travel down the guides to the transfer devices 19 and 20 and the cams 67 and 70, operating in timed relation with each other, will transfer the discs into the notches 74-74 of the feed wheel 17 and 18. As the discs 32-32 are carried around by the feed wheels 17 and 18, they will be drawn past the knives, illustrated by the knife 76, and a radial slit will be cut in each disc by the knives. The slit discs will then be carried around by the feed wheels 17 and 18, being held in the notches 74-74 by the retainers 82 and 78, until the slit discs are forced onto the central conductor 80 travelling from left to right as seen in Fig. 1. After the discs 32-32 are thus applied to the central conductor 80, the tubular outer conductor 83 may be applied over the discs in any suitable manner.

As is apparent from Figs. 4 and 5, the retainers 78 and 82 maintain the slits 77-77 in the discs 32-32 slightly open from the time the slits are cut therein by the knives until the discs reach the central conductor 80 upon which they are applied. This permits the central conductor 80 to enter the slits readily and to slide easily through the slits into the central apertures 79-79 of the discs. The discs 32-32 are carried toward the

central conductor by the feed wheels 17 and 18 along arcuate paths and, consequently, the discs are forced upon the central conductor with a wiping motion. In view of the fact that the slits 77 are held slightly open by the retainers 78 and 82 until the discs reach the central conductor 80 and also because the discs are applied to the central conductor with a wiping motion, no injury results to the forward corners and sides of the slits, such as might occur if the slits were permitted to close before they reach the central conductor and were forcibly opened by the passage of the central conductor therethrough. This is especially important when the insulating discs are made of relatively soft materials, such as polyethylene.

Since the retainers 78 and 82 end at a point adjacent to the central conductor 80, the slits are released as the discs are applied to the central conductor and are free to close after the discs have been placed upon the central conductor. As a result, the slits tend to close up and the discs substantially completely surround the central conductor, somewhat in the manner illustrated in Figs. 11 and 12, thereby insuring the retention of the discs in their proper places upon the central conductor.

The central apertures 79-79 in the discs 32-32 are slightly smaller in diameter than is the central conductor 80. As a result, the central conductor tends to spread open the slits 77-77 in the discs, as is shown in Fig. 12, and the natural resiliency of the discs causes the discs to engage the central conductor firmly. After the tubular outer conductor has been applied over the unit formed by the central conductor and a series of discs applied thereto, the slits in the discs are substantially closed, as shown in Fig. 11, and then there is practically no possibility that the discs will slide along the central conductor.

The apparatus outlined hereinabove obviates the problems that would arise if an attempt were made to slit the discs at the time they are formed, to feed the slit discs from a hopper into a pair of mechanisms with the slits orientated and to advance the discs through the mechanisms to the applicator wheels. Likewise, deformation of the walls of the slits is prevented and the discs so applied to a central conductor engage the conductor firmly. It is difficult to purposely remove discs thus applied to the conductor, much less to remove them accidentally, because the slits tend to close up around the conductor and the conductor is engaged by a substantially solid ring of insulating material, such as is illustrated in Figs. 11 and 12 of the drawings. It is obvious that the location of the slitting step is important and that this invention provides a simple yet effective apparatus for assembling articles, particularly apparatus for the application of insulating discs to central conductors to form units suitable for use in the manufacture of coaxial cables.

While the insulating discs 32-32 preferably are made of polyethylene, the apparatus embodying the invention may be used equally well to apply discs made of other relatively soft insulating materials to central conductors. For example, the insulating discs may be made of cellulose acetate or mixtures of cellulose acetate and cellulose butyrate, or may be fabricated from relatively soft products obtained by polymerizing vinyl compounds, such as are obtained by polymerizing

vinyl chloride and vinyl acetate or mixtures thereof.

What is claimed is:

1. In an apparatus for applying soft annular discs to a conductor, means for feeding a plurality of such discs along a predetermined path and to a conductor, and means adjacent to said path including means for cutting each of the annular discs advanced therewith to form discontinuous annuli, means passing through the resulting cuts in the discs for expanding the cuts and means entering the expanded cuts for maintaining them expanded, said last mentioned means extending to the conductor, whereby the conductor slides freely through the expanded cuts without damaging the discs.
2. An apparatus for use in applying soft annular discs to a conductor, comprising a guide for receiving slotted discs along one side thereof and for guiding the discs to a conductor, the guide being thinner than the diameter of the conductor and being received in the slits in the discs to hold them open, and means in advance of the guide for forming slits in the discs which have a gap no wider than the thickness of the guide, said slitting means including means for expanding the slits in the discs and while the slits are expanded guiding the discs to the guide.
3. An apparatus for applying soft annular insulating discs upon a conductor, which comprises a rotatable feed wheel for advancing such discs to and forcing them upon the conductor, means for cutting slits in the discs carried by the feed wheel and for expanding the slits, and means adjacent to the slit-cutting means for entering the expanded slits in the discs and for maintaining the slits expanded until the discs are advanced to the conductor.
4. An apparatus for applying soft annular insulating discs upon a conductor, which comprises means for longitudinally advancing the conductor, a rotatable feed wheel for advancing such discs to and forcing them upon the moving conductor, a knife adjacent to the feed wheel and in the path of discs carried by the feed wheel for cutting radial slits in the discs and for expanding the slits, and an arcuate retainer adjacent to the knife and in alignment therewith for entering the expanded slits and keeping them expanded until the discs reach the conductor.
5. In an apparatus for applying soft annular insulating discs upon a conductor, means for advancing a plurality of such discs along a predetermined path to the conductor, a knife extending into said path for cutting radial slits in the discs advanced therewith, said knife having a cutting edge of reduced thickness on the side thereof first engaged by the discs and expanding to a greater thickness at the edge where the discs leave the knife, and a guide abutting the exit edge of the knife for entering the slits cut in the discs as the discs leave the knife to prevent the slits from closing, said guide extending to the conductor.
6. An apparatus for applying soft annular insulating discs to a conductor, which comprises means for advancing a conductor longitudinally, rotatable feed wheels for carrying such discs to opposite sides of the conductor and forcing them upon the conductor, means for feeding the discs to the feed wheels, a knife associated with each feed wheel and positioned in the path of the discs carried by its associated feed wheel for cutting radial slits in said discs, each of said knives having a cutting edge of reduced thickness on the

side thereof first engaged by the discs and expanding to a greater thickness at the edge where the discs leave the knife, and an arcuate retainer adjacent to each feed wheel and abutting the exit edge of the associated knife, each of said guides entering the slits cut in the discs as the discs leave the adjacent knife to prevent the slits

from closing and extending to a point close to the conductor, whereby the conductor slides freely through the slits without damaging the discs.
